UNITED STATES PATENT OFFICE.

WILLIAM CAIRNS, OF ELYRIA, OHIO, ASSIGNOR TO THE ELYRIA IRON AND STEEL COMPANY, OF ELYRIA, OHIO, A CORPORATION OF OHIO.

TUBE-FORMING APPARATUS.

SPECIFICATION forming part of Letters Patent No. 734,299, dated July 21, 1903.

Application filed December 12, 1902. Serial No. 134,967. (No model.)

To all whom it may concern:

Be it known that I, WILLIAM CAIRNS, a citizen of the United States, residing at Elyria, in the county of Lorain and State of Ohio, **5** have invented a certain new and useful Improvement in Tube-Forming Apparatus, of which the following is a full, clear, and exact description, reference being had to the accompanying drawings.

10 By the method generally employed for bending metal strips into tubular form the strip or skelp is first bent longitudinally midway between its edges into **U** shape, the sides of the **U** being after this initial bending substantially straight and nearly parallel. This bent trough-like structure is then forced through a suitable former by which these straight sides are gradually bent to bring their edges together, and the tube is finished **15** as well as may be between finishing-rolls. This method of making tubes is objectionable, because it is practically impossible to bend the extreme edges of the skelp into circular arcs, wherefore these edges meet at an obtuse angle and the finished tube is never a **20** complete circle in cross-section.

By the method which the mechanism hereinafter described is adapted to carry out the skelp is first bent longitudinally along both **25** its edges into the circular arc form which they ought to have in the finished tube; and then the intermediate part of the skelp is bent gradually and progressively toward the longitudinal center thereof until the initially-curved edges are in contact, and thereby there is formed a tube which is a perfect circle in cross-section.

The invention relates to mechanism for bending the skelp into tubular form by the **30** method last above referred to; and the invention may be here summarized as consisting in the construction and combination of parts hereinafter described, and pointed out definitely in the claims.

35 In the drawings, Figure 1 is a side elevation of the mechanism embodying my invention. Fig. 2 is a plan view thereof. Fig. 3 is a front view of the rolls for initially bending the skelp. Fig. 4 is a plan view of the former into which the initially-bent skelp passes after leaving the forming-rolls. Fig. 5

is a side view, partly in longitudinal vertical section, of said former. Figs. 6, 7, 8, 9 and 10 are respectively transverse vertical sectional views of said former in the planes of **55** lines 6 6 7 7 8 8 9 9 10 10, respectively.

Referring to the parts by letters, A B represent two forming-rolls mounted in suitable housings C C. On the periphery of the roll A is an annular tongue a, which is fitted to **60** the annular groove b in the periphery of the roll B, the space between the tongue and groove being of the shape in which it is desired to initially bend the skelp. The face of the tongue a is flat; but the sides thereof **65** are curved into circular arcs of something less than ninety degrees of the same radius as the finished tube is to be, and the groove b is similarly formed.

D and E represent two finishing-rolls **70** mounted in suitable housings C a suitable distance from the rolls A B. Each of these rolls D and E has a substantially semicylindrical groove in its periphery, one of which grooves is indicated by d in Fig. 2. Between **75** these pairs of rolls is a former, having between the fixed bottom plate G and the removable cover-plate F; which rests upon the bottom plate, a channel, which at the entrance end is shaped to fit the bent skelp as **80** it emerges from the forming-rolls A and B—that is to say, this channel is flat in its middle part; but at its sides it is curved upward in circular arcs. In assuming the cylindrical form the flat middle part of the channel gradually grows narrower, while the curved sides **85** thereof gradually increase in length without change in the radius of curvature. The change of the form is gradual and such that the curve initially given to the edges of the **90** skelp is gradually extended inward toward the longitudinal center, which is the last part of the skelp to be given this circular curve.

A mandrel M, which is anchored to the cover-plate at a suitable point, extends **95** through this channel and out of the discharge end thereof and to a point between the finishing-rolls D E. As the skelp is bent by the former the edges are carried over and around this mandrel. On the inner side of the cover-plate there is a centrally-placed longitudinal tongue f, of gradually-decreasing width,

which always lies between the approaching edges of the skelp, and thereby prevents the unequal bending of the skelp on opposite sides of the longitudinal center thereof. This 5 tongue also holds the mandrel down, so that it shall always be the proper distance from the bottom of the channel.

The cover-plate F is made of two parts, of which the part f covers the receiving end of 10 the channel and the part f' covers the delivery end. At the receiving end of the former both the bottom plate and cover-plate are curved to fit the curvature of the rolls A B, between which they pass as far as practicable—that 15 is to say, these curved edges touch or almost touch the faces of the rolls just behind the plane in which these rolls are nearest together. The part f of the cover-plate projects at its other end under a lip f², projecting 20 from the part f'. A set-screw H passes through a lug f³ on top of the part f and engages with the end of said lip f². By turning the set-screw the position of the part f relative to the rolls A B may be regulated. 25 The part f' of the cover-plate is held down upon the base-plate by the following means, to wit: Two lugs g' project upward from the base-plate on opposite sides of the cover-plate, and their projecting upper ends are undercut. Two lugs f⁵ extend laterally from 30 the cover-plate and are beveled to fit beneath the undercut portion of said lugs. Near the opposite end of the cover-plate there are two side lugs g², extending up from the base-plate, which are also undercut. A wedge-shaped key N, resting upon the cover-plate, 35 bears at one side against a shoulder f⁶ thereon, while its other edge is beveled and engages beneath the undercut portions of the 40 lugs g².

K represents a guide for delivering the skelp properly to the rolls A B. As shown, it is a trough-like plate having a cover k, whose upward movement is prevented by the 45 overhanging lugs k'.

In using the described apparatus the skelp J is first cut into V shape at its front end, so that it may enter between the rolls A B. The skelp is then pushed along in the guide K by 50 hand or by mechanism, as deemed advisable, until the pointed front end thereof passes between the rolls A B. Thereafter these rolls not only initially bend the sides of the skelp, but also force it along through the former G, 55 by which it is curved, as stated. When it emerges from the former, it is almost a cylinder, and it embraces the mandrel, the front swelled end m of which lies between the two

finishing-rolls D E. These rolls complete the tube, bending it closely over the swelled end 60 of said mandrel.

Having described my invention, I claim—

1. In an apparatus for forming tubes, the combination of two forming-rolls having respectively a tongue and groove whose faces 65 are flat and whose sides are curved in circular arcs, with a former into which the bent skelp is delivered from said rolls, which former contains a channel which fits the bent skelp as it is delivered from said roll, and which gradually assumes a circular form in cross-section, a mandrel in said channel anchored to the top wall thereof and extending out of the delivery end, and two grooved finishing-rolls between which the end of said 75 mandrel projects.

2. In an apparatus for forming metal tubes, a former consisting of a base-plate and a removable cover-plate between which is a channel having a flat center of gradually-decreasing width from the receiving to the delivery end thereof and having arc-shaped sides which increase in length without changing the radius of curvature. 80

3. In an apparatus for forming tubes, a 85 former consisting of a base-plate, and a cover-plate, between which is a forming-channel, said cover-plate being formed in two parts of which the part covering the delivery end of the channel has a lip which overhangs the 90 part covering the receiving end thereof, a set-screw carried by one of said cover-plate sections and engaging with the other, and means for securing together the base-plate and that part of the cover-plate which is at 95 the delivery end of the former.

4. In an apparatus for forming metal tubes, a former curved at its front end to fit the curvature of a pair of rolls, and consisting of a fixed base-plate, and a cover-plate which 100 rests upon the base-plate, and is formed of two parts of which the part, whose front end is curved, lies beneath a lip on the other part, a set-screw carried by the front part and engaging with the other part, there being between the base-plate and the two-part cover-plate a forming-channel, and means for securing together the base-plate and that end of the cover-plate which is at the delivery end of said former. 105

In testimony whereof I hereunto affix my signature in the presence of two witnesses.

WILLIAM CAIRNS.
